PROTECTING DEVICE FOR ELECTRIC DETONATORS

Daniel D. Huyett, Wilmington, Del., assignor to
 Atlas Powder Company, Wilmington, Del., a
 corporation of Delaware

Application May 28, 1938, Serial No. 210,564

2 Claims. (Cl. 102—10)

This invention relates to a protecting device for electric detonators, and more particularly to the type of protecting applied to the uninsulated portion of the lead-in wires of electric detonators and generally referred to as a "shunt."

An object of the invention is to provide a protecting device which will more surely guard against the detonator being prematurely exploded should its lead-in wires accidentally contact a source of electricity.

A still further object of the invention is the provision of a protective shunt which may be pressed firmly upon the lead-in wires of the detonator without injuring them, but which may be readily removed from the wires when it is desired to connect the wires for firing the shot.

Other objects of the invention will hereinafter more fully appear.

Figure 1 is an elevation of an electric detonator and its lead-in wires having the protecting device of the present invention applied thereto.

Figure 2 is a sectional view on line 2—2 of Figure 1.

Like numerals designate corresponding parts in both of the figures of the drawing.

Referring to the drawing, 1 designates the casing of an electric detonator and 3 and 4 the insulated lead-in wires, usually of copper or iron wire, which extend from the casing. Within the detonator, the lead-in wires are attached to an igniting element 8, and at the outer end the lead-in wires have uninsulated portions 3a and 4a, which may be readily attached to a source of electricity. In the ordinary use of such a detonator, flow of sufficient current through the igniting element 8 explodes the detonator.

To prevent premature firing of the detonator by stray currents, a protecting device or shunt 5 is applied to the lead-in wires at a point closely adjacent the termination of the insulation. As long as this shunt is in place, current accidentally applied to the uninsulated portions 3a and 4a of lead-in wires will short-circuit through the shunt 5 and premature firing of the igniting element 8 is thereby prevented.

Heretofore, in protecting devices of this character, difficulty has been had in securing good contact between the shunt and the lead-in wires to assure short-circuit without subjecting the lead-in wires to injury upon application or removal of the shunt. When relatively soft metals such as lead were employed to obtain good contact with uninsulated portions of the lead-in wires, it was found that upon application of 55

heavy currents to the outer ends of the lead-in wires, the relatively soft metal would frequently melt and fall away from the wires, thereby permitting current to go through the igniting element and explode the cap. On the other hand, where relatively hard metals of high melting point were employed for shunt purposes and compressed about the wires with force insufficient to injure the wires, poor contact frequently resulted, thereby increasing the resistance across the shunt. This increased resistance resulted in a greater proportion of the current passing through the filament and frequently in the explosion of the detonator.

In accordance with the present invention, the shunt or protecting device is made of laminated material having a layer of soft metal of low melting point, such as lead, tin or lead-tin alloy, adjacent to and in contact with the lead-in wires and an outer layer of relatively hard metal of relatively high melting point. The metal of the outer layer has a hardness and melting point not less than that of annealed or soft temper 99% plus pure, aluminum strip sheet, of Brinell hardness 23 @ 500 kg., and melting point of about 1215° F. Suitable metals for the outer layer are, for example, aluminum, silver, copper, bronze, brass, iron and steel. Various alloys of the required hardness and melting point may be employed as the outer layer. Preferably, the outer layer of metal is of sufficient strength and toughness to withstand bending 180° without fracturing or weakening, and is of low resilience so that the shunt may be bent about and pressed upon the lead-in wires, and will thereafter remain tight and not tend to spring off. Materials having the required properties for the outer layer of the shunt, and which at the same time are readily adaptable to the shunt fabrication operations usually employed, are aluminum, copper, soft steel and certain of the copper base alloys.

In the embodiment of the invention shown in Fig. 2 of the drawing, the shunt 5 is in the form of a strip of laminated material electrically connecting and partially embracing an uninsulated portion of each of the lead-in wires. The laminated material has an outer layer 6 of metal having a hardness and melting point not less than that of aluminum, as for example, copper and an inner layer 7 of relatively soft metal of relatively low melting point, such as lead, tin or lead-tin alloy.

The two wires are located close together well

back near the bend of the metal and the lead surfaces are pressed tightly together forming an excellent contact with the wires. Though pressed tightly upon the wires, the relatively soft metal does not injure the wires and renders the shunt readily removable from the wires without injury thereto.

When heavy current is applied to the outer ends of the lead-in wires and the current is of sufficient strength to melt the inner layer of soft metal, the outer, protective layer of metal of relatively high melting point holds sufficient molten metal in contact with the wires to maintain the short-circuit. The melting of the inner layer tends to increase the degree of contact of the shunt with the wires, and at least a portion of the molten metal appears to be held in the crevices adjacent the lines of contact of the wires and shunt by capillary attraction, as the molten metal tends to be retained in contact with the wires in sufficient quantity to maintain the short-circuit even though the wires be moved.

Repeated tests of copper-lead laminated protecting devices embodying the present invention by subjecting the outer ends of copper lead-in wires to which they were applied to heavy currents, have shown that copper lead-in wires employed in commercial detonators will always melt and break the circuit before the cap will fire, due to resistance in or breakdown of the shunt. No other shunt with which I am familiar will consistently pass this test.

Preferably, the materials employed for the manufacture of these shunts have the relatively soft layer of lead, lead-tin alloy, or the like, bonded to the relatively hard, high melting point material, such as copper, bronze, iron or steel. Such bonding may be accomplished by tin-plating the copper, bronze, iron or steel, and thereafter rolling lead on the tin-plated surface under heat and pressure, so that a lead-tin alloy is formed at the jointure of the two metals, thereby bonding them together. When such bonded, laminated material is employed, and the shunt is subjected to current density sufficient to melt the inner layer of relatively soft metal, good wetting contact at the surface interface between the two metals is assured, thereby aiding the capillary attraction and increased degree of contact described above. A laminated material formed by sweating a .015" layer of lead to a tinned copper layer of about .015" has been found to be excellently suited for the production of a protective device employed on 20 to 22 gauge lead-in wires. It is

to be understood, however, that other materials and other thicknesses of metal may be employed without departing from the invention. Where it is desired to protect the outer layer of metal from corrosion and the like, a third outer layer of corrosive-resistant metal may be employed.

Although the embodiment of the invention chosen for purposes of illustration is in the form of a clip, partially embracing uninsulated portions of the wires, it is to be understood that the invention is not to be considered as limited in this respect as the protective device can be in other form such as a tubular, laminated body through which the bare portions of the wires are threaded and which body has been compressed about the wires, so long as the lamination is such that the relatively soft metal of relatively low melting point is adjacent to and in contact with the wires. Other modifications will be apparent to those familiar with the art.

Having described my invention, what I claim is as follows:

1. In a detonator assembly having a detonator and lead wires therefor; a shunt for electrically connecting an uninsulated portion of each of the wires and adapted to be readily removed therefrom, said shunt comprising a strip of laminated metal dimensioned and bent so that when positioned upon uninsulated portions of the lead wires and pressed thereon, said lead wire portions are embraced in substantially parallel relation near the bend in the strip, said laminated metal having a first inner layer adapted to be in contacting engagement with the wires and consisting essentially of metal taken from group consisting of lead and tin, and a second layer of metal exteriorly positioned with respect to said first layer and adapted to be separated from said wires by means of said first layer, said second layer of metal having a hardness and melting point not less than that of aluminum, said shunt being so constructed that when pressed upon the lead wires the second layer of metal is close enough thereto so that upon melting of the inner layer of metal due to the application of current to the wires, a quantity of molten metal of the inner layer sufficient to maintain the electrical connection across the wires will be retained in contact with the wires.

2. A shunt for detonator lead wires as set forth in claim 1 and wherein the first layer is bonded to the second layer by means of a lead-tin alloy.

DANIEL D. HUYETT.
